CLAIM

The ornamental design for a curved pocket wedge, as shown and described.

DESCRIPTION

FIG. 1 is a front top perspective view of the curved pocket of the present invention;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is a back bottom perspective view thereof.

1 Claim, 8 Drawing Sheets
